DRILL RIG

Scott A. Fuller, Oakland, Calif.

Application December 20, 1944, Serial No. 563,953

6 Claims. (Cl. 77—27)

1

The invention relates to a portable machinist's drill.

The broad object of the invention is the provision of an improved portable machine for drilling holes and performing other cutting operations on structural members already in place, or which for some other reason cannot be taken to a drill press. More specifically objects of the invention include the provision in such a machine, of safety devices for preventing breakage of bits, and injury to the workman; of devices for the more convenient erection and handling of the machine at the job site; and of precision adjuncts for the setting and operation of the cutting bits within small tolerances previously unknown with tools of this general type.

My invention possesses other objects and features of value, some of which with the foregoing will be set forth in the following description of the invention. It is to be understood that I do not limit myself to the showing made by the said description and the drawings as I may adopt variant forms of the invention within the scope of the appended claims.

Referring to the drawings:

Figure 1 is a front elevation of a drill rig embodying my invention. Portions of the structure are omitted and other portions are sectioned to more clearly disclose the construction.

Figure 2 is a cross-sectional view, the plane of section being indicated by the line 2—2 of Figure 1.

Figure 3 is a cross-sectional view through the arm and feed screw link, the plane of section being indicated by the line 3—3 of Figure 1.

In many kinds of building operations, including the construction of ships and water borne vessels of all types, as well as the erection of steel work in land building, it is necessary to perform various cutting operations on structural members after they have been erected in place, or in preparation for such erection. Such operations include drilling, counterboring, reaming and not infrequently surface facing of bearing bosses, sometimes on the far side of the member.

These operations, especially in the steel work of ships, may have to be done on members lying at various angles to the horizontal; or perhaps the operation must be carried out on the underside of a deck beam, or in a restricted area such as a corner. In all places where machines of this type are in use, they are recognized as dangerous to the operator; and given to costly breakage of the drills which are the cutting tools most frequently used with them.

2

After drilling a hole, it is frequently desired to ream it to size, or perform some other operation about the same center; or perhaps remove and replace the drill or other cutting tool. When close accuracy is required, these things are not easily or quickly done with the portable drills commonly available in the shipyards.

In the drill rig of my present invention, I have tried to meet these needs and provide a precision mechanism readily set up, and with which all operations within its range may be quickly and accurately performed with safety to the operator and a minimum of breakage. This application is a continuation-in-part of my copending application of the same title, Serial No. 490,740, filed by me June 14, 1943, which application I abandoned subsequent to the filing of the present application.

In terms of broad inclusion, the drill rig of my invention comprises an extensible supporting column having an automatically adjustable foot at one end and a manually adjustable head screw at the other end, so that the column may be set up or erected in stable condition between floor and ceiling elements, or between any conveniently placed structural members. Slidable axially of the column and rotatably mounted thereon are a pair of arms, one extending out laterally from the column; and the other pivotally mounted with respect to the first and selectively extending at a right angle thereto in clock-hand fashion.

The arms are for supporting a motor, which rotates the drill or other cutting bit; and means are provided for fixedly securing the motor to a selected arm and for controlling it so that the bit is advanced into the work or withdrawn as required. Inseverable key means are also provided to lock the arms and column rigidly together, and to be operated either to lock or unlock the parts by a hammer blow.

To make accurate resetting of the tools possible, means are provided for locating the position of the supporting arm by impingement against fixed stops adjustably positioned on the column.

In greater detail, my drill rig comprises a cylindrical supporting column formed of the telescoping tubes 2 and 3. These tubes are fixed in rough adjustment relative to each other by a pin 4 passing through a hole near the top of the lower and outer tube 2, and a selected one of the holes 6 in the smaller and inner tube.

The lower end of tube 2 is filled with a block 7 welded or otherwise fixed in place and having a wing 8, extending therefrom on which a shoe 9 is pivotally mounted by the pin 11. The shoe is

provided near each end with hardened points 12, which bite into the supporting surface to which the shoe automatically adjusts itself because of its pivotal mounting.

The upper end of the tube 3 is similarly closed with a block 13, through which the head screw 14 is threaded. The head screw is provided with a hardened point 16, and is rotated to jam the point 16 into the upper supporting structural member, by the knobbed handle rod 17 loosely carried in the enlarged body 18 of the screw. A lock nut 19 provides means for securing the screw after setting. It is clear from the above that the pivoted two-point support of the column at the bottom, and the single point at the top provide efficient means for setting up the column between spaced structural members, even though not parallel; and that the column is held securely against lateral displacement and rotary movement about its own axis.

Slidably mounted on the column is a sleeve or hub or collar 21 which is also rotatable on the column. On diametrically opposite sides, the sleeve is formed with heavily thickened walls to form extensions 22 and 23, the latter being continued outwardly laterally of the column in the arm 24, having the shape of an inverted T. The horizontal flange (cross bar of the T) of the arm merges into the lower bead 26 of the sleeve, which on the opposite side of the sleeve from the arm merges into the large flat boss 27, which forms the face or end of the extension 22. At the upper margin of the sleeve, the bead 28 extends from the top portion of the boss 27 around the sleeve and extension 23 to merge with the vertical web or flange of the arm. The construction just explained is of great importance since in operation, it is subjected to stresses of considerable magnitude; and any failure at this point would be fatal to the success of the job underway at the time, as well as dangerous to the operator.

The length of the arm 24 may be varied within readily ascertained practical limits. I have found an arm about 21 inches long on a column having a diameter of 2½ inches quite satisfactory.

It will be noted that the face of the boss 27 lies in a plane perpendicular to the plane of the under side of the arm 24. Rotatably mounted on this boss is a second T-shaped arm 29, which may be selectively adjusted to extend radially like a clock-hand in any direction from its rotary axis. The arm is formed on one side of a hub 31, which terminates in a plate or flange 32, provided with a short extension 33, rotatably seated in a complementary bearing formed in the face of the boss 27. A screw 34 through the hub 31, and threaded into the thickened wall 22 of the sleeve, is turned by the swivel handle 36, and provides convenient means for fixing the arm 29 in adjusted position. It will be readily apparent that with clock-hand adjustment of the arm 29 on the sleeve, and the rotary and axial adjustments of the sleeve on the column, the end portions of the arm 24 or the arm 29 can be quickly located in substantially any desired position.

Supported on a selected one of the arms, as for example the horizontal arm 24, as shown in Figure 1, is a prime mover or motor 41, by which the drill 42, or other cutting tool or bit is held and driven. The motor may be of electric or air type, and its housing is provided with handles 43 by which the counter torque resulting from rotating the cutting tool is carried. The cutting tool or drill 42 as shown in Figure 1 may be the

common type with a taper shank 44 engaging a socket formed in the rotor shaft 46.

The means for supporting the motor and controlling the feed of the cutting tool comprises a link 47, threaded at one end into the motor housing 41 and having a ball 48 at the opposite end rotatably and pivotally held in a socket formed in the ring 49, which is part of a bracket carried by the arm 24. The link thus performs both the functions of a link supporting the motor from the arm for a universal movement thereon, and a feed screw to move the motor and its drill toward and away from the work. Fats 51 on the upper part of the link provide a wrench hold by which the link is manually turned.

The universal mounting of the link permits an important adjustment of the drill laterally, under conditions which would make setting difficult and slow if the motor and drill were held rigidly in a fixed axis. It also permits drilling in an axis not in parallelism with the axis of the supporting column, which means that the column may be set up with less care and accuracy than would otherwise be necessary for close work.

Because the feed screw link is capable of controlled feeding in either direction, my rig may be used, with appropriate cutting tools, for spot-facing even on the far side of a structural member from the motor. Perhaps the most important advantage of the feed screw link assembly, at least from the view point of the operator's safety, is its complete control of the movement of the drill, so that the tendency of the drill to "hog in," when the point breaks through or for any other reason, is under effective restraint and the regular and desired feeding movement is continued through the critical moment.

The socket ring 49 also performs an additional function, which is that of a clamp or locking means for fixing the bracket slide 52 rigidly on the arm. The socket ring is formed like a star hand-wheel with short spokes or lugs, extending from the central ring to facilitate turning it in the bracket slide into which it is threaded as best shown in Figure 3. The bracket slide 52 comprises a main body or ring with internal threads 54 to receive the threads of the socket ring, and provided with opposite grooves 55, so that it may be slipped over the end of the arm, the lugs 56 then bearing on the upper face of the horizontal flange of the arm; and the end face of the socket ring bearing against the lower face of the flange when it is tightened. Because the bracket is most conveniently moved the short distance for fine adjustment by tapping with a hammer, tapping lugs 57 are formed on opposite sides of the bracket body, these lugs being spaced from and lying directly below the arm as shown in Figure 1.

The proportions and arrangement of the parts is such that only a small amount of turning of the socket ring engages or frees the end face of the ring from the under side of the arm, so that the bracket is securely fixed to the arm or freed for adjusting movement along the arm, as the case may be. When the bracket is locked to the arm, the under face of the arm provides the opposing surface of the socket in which the ball is seated; and preferably the under side of the arm is milled to provide a shallow cylindrical groove 58, so that thrust of the ball during operation of the drill may be most suitably distributed and carried, without the ball being loose or bound in its socket, but held therein as in a journal bearing.

The end of the link 47 is preferably provided

with a short small extension or pin 61 which may be impinged against the end of the drill shank to release the drill. From the foregoing it will be obvious that as occasion requires, the socket ring may be loosened and the bracket assembly moved to the other arm, where the operation is substantially the same as that explained, except that the axis of the cutting tool operation is more in the horizontal plane than the vertical.

The construction of the driving motor 41 is no part of my invention; and of various motors which are available, I have selected one having a threaded socket 62 to cooperate with the threaded male end of the feed screw link. Where motors are provided with other means for the mounting of the link, the link is complementarily formed.

Means are provided for rigidly but releasably securing the sleeve-arm assembly to the column. Cut in the thickened wall 23 of the sleeve is a keyway, tapering in depth as shown in Figure 1. A wedge key 66 shaped cylindrically on the inner edge to match the column, is seated in the keyway and prevented from falling out when the parts are assembled by both head and tail lugs 67 and 68. Since the sleeve is frequently removed from the column, means are provided for retaining the key in the keyway, so that loss will not occur. This is accomplished by forming in the side of the key a shallow groove 69 into which projects a stud on the end of the screw 71, set in the sleeve wall. Thus the key may be loosened or tightened by the blow of a hammer, but cannot be lost or mislaid when the sleeve-arm assembly is separated from the column.

Since it is frequently necessary to change cutting tools, or for other reasons, lift the drill and swing it to one side, means are provided for retaining the setting of the arm so that the cutting tool may be returned after any change, to the same center or axis of rotation it previously occupied. Partially encircling the column 2, immediately below the sleeve is a stop collar comprising a heavy body 73 and curved arms 74, and which performs a number of functions. A notched draw-bolt 75 extends through the thickened body of the collar, the curvature of the notch matching that of the column; and a nut 76 threaded on the end of the bolt permits tightening of the bolt against the column to lock the stop collar thereon. A spring wire circlet 77 seated in an annular groove at the butt end of the bolt prevents its separation from the collar when the collar is removed from the column.

Preferably the ends 78 of the stop collar arms 74 are separated circumferentially by at least 90° of arc; and the arrangement is such that these ends lie on opposite sides of the key 66 which extends downwardly between them. It will at once be seen that the stop collar when secured in place, not only serves as a stop or bearing upon which the sleeve-arm assembly may turn on the column, so that it need not be lifted or jockeyed into place after once being set at the desired height, but by setting one or the other arm end 78 snugly against the key after the drill or cutting tool has been set, a permanent stop is provided for resetting the tool in case it must be moved or changed before the operation is done. This of course means that with the stop collar set in position, operation of the cutting tool may be interrupted, the key loosened, the sleeve-arm assembly raised and turned to swing the motor to one side, and the tools changed as required, then all moved back to exactly the original position for a continuance of the job about the same axis or

center of cutting, which may or may not require the use of suitable bearing bushings in the hole first drilled, or adjunctively secured on the work, in accordance with practice well known to the skilled machinist.

5 I claim:

1. A drill rig of the character described comprising a supporting column, an arm extending laterally of the column, a sleeve to which the arm is secured and adjustable rotatably about the column and axially thereof, means for locking the sleeve to the column in adjusted position, a second arm connected to the sleeve, and a feed screw having means for selectively engaging either arm.

10 2. A drill rig of the character described comprising a supporting column, an arm extending laterally of the column, a sleeve to which the arm is secured and adjustable rotatably about the column and axially thereof, means for locking the sleeve to the column in adjusted position, a second arm rotatably connected at one end to said sleeve for adjustment to different radial positions at right angles to the first arm, and a feed screw having means for selectively engaging either of said arms.

25 3. A drill rig of the character described comprising a supporting column, an arm extending laterally of the column, a sleeve to which the arm is secured and adjustable rotatably about the column and axially thereof, means for locking the sleeve to the column in adjusted position, a second arm carried by the second plate and extending at an angle to the first arm, means for locking the second 30 plate in selected rotative position, and a feed screw having means for selectively engaging either of said arms.

40 4. The combination of an arm for supporting a motor by which a drill is held and driven, of a bracket slidable on the arm and having an opening therein, a clamp ring threaded into said opening and seating against the arm, said ring and arm providing a ball socket, and a link for supporting the motor and having a ball-end in said 45 socket.

5. In a drill rig, a cylindrical column, a sleeve movably mounted on the column and having an arm thereon for carrying the drill, a collar adjustably fixed on the column and on which the sleeve bears axially, spaced stops on the collar, and a stop on the sleeve between the spaced stops for limiting rotary movement of the arm on the column.

55 6. In a drill rig, a cylindrical column, a sleeve movably mounted on the column and having an arm thereon for carrying the drill, a collar adjustably fixed on the column and on which the sleeve bears axially, spaced stops on the collar, and a wedge key for locking the sleeve to the column and extending between said spaced stops.
